Primary Examiner — Carla J Wright(74) *Attorney, Agent, or Firm* — Dinsmore & Shohl LLP(57) **CLAIM**

The ornamental design for a sleeve for electronic device, as shown and described.

DESCRIPTION

FIG. 1 is a front, top, and side perspective view of a sleeve for electronic device showing our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines in the drawing figures form no part of the claimed design and depict portions of the sleeve for electronic device that form no part of the claimed design.
